CLAIM

We claim the ornamental design for a medication packaging and dispensing system, as substantially shown and described.

DESCRIPTION

FIG. 1 is a front perspective view of a medication packaging and dispensing system including a lid shown in a closed position.

FIG. 2 is a front elevational view of the medication packaging and dispensing system shown in FIG. 1.

FIG. 3 is a rear elevational view of the medication packaging and dispensing system shown in FIG. 1.

FIG. 4 is a right side elevational view of the medication packaging and dispensing system shown in FIG. 1.

FIG. 5 is a left side elevational view of the medication packaging and dispensing system shown in FIG. 1.

FIG. 6 is a top view of the medication packaging and dispensing system shown in FIG. 1.

FIG. 7 is a bottom view of the medication packaging and dispensing system shown in FIG. 1.

FIG. 8 is a front perspective view of the medication packaging and dispensing system shown in FIG. 1 with the lid shown in an open position and an inner panel shown in a closed position.

FIG. 9 is a top view of the medication packaging and dispensing system shown in FIG. 8.

FIG. 10 is a front perspective view of the medication packaging and dispensing system shown in FIG. 1 with the lid shown in the open position and the inner panel shown in the open position; and,

FIG. 11 is a top view of the medication packaging and dispensing system shown in FIG. 10.

FIGS. 1-11 are various views of a medication packaging and dispensing system in accordance with the present design. The medication packaging and dispensing system includes a container and a tray insert.
